COVERING MACHINE

James P. Shorrock, Holyoke, Mass., assignor to
 B. F. Perkins & Son, Inc., Holyoke, Mass., a
 corporation of Massachusetts

Application May 17, 1932, Serial No. 611,890

11 Claims. (Cl. 117—34)

This invention relates to improvements in machines for uniting a plurality of elements or serving covering elements about a core element.

The principal objects of the invention are directed to the provision in a machine for uniting elements or for serving or covering a core element with other elements of means wherein the elements are suitably guided and tensioned for the uniting or covering operation. Various novel features and advantages of the invention will be more fully hereinafter referred to in connection with the accompanying description of the novel combination and arrangement of parts constituting the invention, reference being had to the accompanying drawing wherein:

Fig. 1 is an elevational view of an apparatus of the class described having the novel features of the invention associated therewith.

Fig. 2 is a partial sectional view at a larger scale showing certain novel features of the invention, and

Fig. 3 is a fragmentary elevational view to explain certain features of the invention.

Referring now to the drawing more in detail the novel features of the invention will be fully described.

In Fig. 1 there is shown an apparatus which may consist of one or more spindle units indicated by 2 and 4. In the form of the invention at present preferred two spindles are shown, one above the other and they may be used to serve an outer element or elements about an inner core element as will appear, but it will be understood the apparatus may be used to unite by twisting or throwing a number of elements.

Each of the spindle units preferably includes a rotatable spindle 6 which spindle in the form of the invention shown may be associated with a rotating part of a motor enclosed within a housing 8 which is suitably supported by frame 10. A take-up member 12 which may be in the form of a spool or drum is rotatable above the spindles and a transversely reciprocating bar 14 as in the said application is provided for leading the finished product onto the take-up member. Guides 16 having openings 17 therethrough are suitably supported by supporting structures 18 shown extending from the frame 10.

The spindles 6 referred to are preferably hollow to permit material such as a core element C to pass therethrough and have portions on their upper ends to receive spools or packages represented by S. These spools or packages may have wound thereon yarn, filaments or other ele-

ments indicated by E, and will be called yarn packages.

A guide cap indicated generally by 20 is provided for each spindle and will be described in detail to facilitate a clear understanding of the novel features thereof. The cap has a body portion having a central hub portion 22 as shown which is suitably bored to fit and receive the upper end 6' of the spindle and is hollowed out as at 24 so that its lower end 25 is in the form of a skirt or flange to encircle the upper end of the yarn package S. Annular guideways 28, 30, 32, and 34 disposed one above the other are provided on the cap and decrease in diameter upwardly from the lower one. Travelers t which may be more or less circular in shape as shown in Fig. 3 are slidable around the annular guideways. The cap is removable from the spindle to permit packages to be placed on and taken off the spindle.

To facilitate a clear understanding of the operation of the cap it will be assumed that a core C in the form of a yarn or filament of metal or rubber is being passed upwardly through the spindles 6 and onto the take-up spool and that it is desired to cover or serve the core with covering elements or filaments which may be carried by the yarn packages. The filaments from the packages are passed upwardly through the travelers t and onto the core C. With the spindles in rotation the packages S will be rotated as will the caps 20 so that the elements will be carried around and wound or served about the core. As will be seen with particular reference to Fig. 3 an element E is guided at spaced intervals from a point adjacent the upper end of the spool to an upper point adjacent where it passes onto the core whereby the element is held against ballooning.

A cap rotates with its spindle so that the relative movements between the travelers and the guideways therefore is not great, at least only enough to allow the core to take up the element, or allow the element to be wound about the core. Therefore appreciable frictional action between the travelers and the guideways is eliminated as distinguished from the condition where a traveler slides around a non-rotating guideway. This is all to the end that a very delicate element may be wound onto the core without being burdened with excess tension and makes it possible to wind an element about the core with the desired degree of tension and uniformity and without such over tension as will either cause the ele-

ment to pull the core sideways or will strain the element itself.

As a further feature where it is desired to wind relatively flat or at least non-round elements or filaments about the core a guiding horn 39 is provided at the upper side of the cap which has a rounded end or rounded circumferential ironing surface 41 against which the filament may bear. As shown in Fig. 3 as a somewhat flat filament travels around the edge 41 and upwardly onto the core it is flattened out or turned so that it is guided in proper position and without twisting as it passes onto the core.

It may be desirable in some cases to provide packages with a multiplicity of separate elements or ends wound thereon. In such a case one of the elements may be passed upwardly through one or more of the travelers t while another element may be passed upwardly through one or more of the other travelers t all to the end that one end or filament may be guided independently of another and onto the core, each with the proper tension and in the manner desired, held against ballooning.

As will be seen an element E is taken on by the core C at a point between the lower end of the guide 16 and the upper end of the cap 20 and the uppermost traveler operates to guide an element in close proximity to the point where the element and core are united. The element between the upper and lower travelers is held against ballooning or whipping to bring about uniform covering and the important uniform tension minus distorting of the core.

As a special feature of the invention, I provide means to facilitate lubrication of the travelers as they travel about the guideways. This is accomplished in one way by means of washers L within the guideways and receivable in suitable recesses as shown. The washers are preferably of some fibrous material such as felt and may be saturated with lubricant. As the cap rotates the lubricant is thrown outwardly from the washers onto the guideways to provide the lubrication therefore.

In some cases it may be desired instead of covering a central core element with a covering element to twist or throw an element from one spool with an element of another spool or to twist elements of either spool with one or more of those of another spool. This may be accomplished by bringing the elements together above the cap and passing them through the travelers.

From the foregoing, it will be apparent that the apparatus is adapted to insure accuracy and excellence of product in connection with operations where it is desired to unite elements of various materials. It is desired therefore to be limited, if at all, by the appended claims rather than by the foregoing description. What I desire to claim and secure by Letters Patent of the United States is:

1. In a machine for uniting filaments comprising in combination, a rotatable spindle for carrying a yarn package, a cap rotatable with said spindle above said package, annular guideways on said cap spaced one above the other, upper guideways being relatively smaller in diameter than guideways therebelow and travelers slideable around said guideways for guiding material at spaced intervals from said package upwardly and inwardly towards the axis of rotation of said spindle and cap.

2. In a machine for uniting filaments comprising in combination, a rotatable hollow spindle

having a portion for receiving a filament package, a cap rotatable with and removable from said spindle to overlie a package thereon, separate annular guideways on said cap one above the other and travelers slideable therearound for receiving and guiding material at spaced intervals from a package on said spindle upwardly and inwardly onto a core passing through said spindle, the said guideways being successively less in diameter upwardly of said cap.

3. In a machine for uniting filaments comprising in combination, a rotatable hollow spindle having a portion for receiving a filament package, a cap removable from said spindle to overlie a package thereon, separate annular guideways on said cap disposed one above the other and travelers slideable therearound for receiving and guiding material at spaced intervals from a package on said spindle upwardly and inwardly onto a core passing through said spindle, the said guideways being successively less in diameter upwardly of said cap, and a part at the upper side of said cap adjacent the uppermost guideway having a surface against which material from a package may bear to prevent twisting thereof.

4. A guide cap for a rotatable spindle adapted to rotate a yarn package comprising in combination, a body having a hub provided with a spindle receiving bore, a skirt for encircling a package on said spindle, annular guideways disposed in spaced relation one above the other and decreasing upwardly in diameter from the lowermost guideways with the lowermost guideway surrounding the upper end of said package.

5. A guide cap for a rotatable spindle adapted to rotate a yarn package comprising in combination, a body having a hub provided with a bore for receiving a spindle, a flange around the lower side of said body, an annular guideway on said flange, other spaced guideways thereabove, upper guideways being relatively less in diameter than an adjacent guideway therebelow, travelers slideable around said guideways and a guiding horn at the upper side of the cap of less diameter than the uppermost guideway.

6. In a machine for uniting filaments comprising in combination, a rotatable hollow spindle having a portion for receiving a filament package, a cap removable from said spindle to overlie a package thereon, separate annular guideways on said cap one above the other and travelers slideable therearound for receiving and guiding material at spaced intervals from a package on said spindle upwardly and inwardly onto a core passing through said spindle, the said guideways being successively less in diameter upwardly of said cap, and lubricating washers around said cap disposed within said guideways.

7. In a machine for uniting filaments comprising in combination, a rotatable hollow spindle having a portion for receiving a filament package, a cap removable from said spindle to overlie a package thereon, separate annular guideways on said cap one above the other and travelers slideable therearound for receiving and guiding material at spaced intervals from a package on said spindle upwardly and inwardly onto a core passing through said spindle, the said guideways being successively less in diameter upwardly of said cap, the said cap being provided with recesses within said guideways and lubricating washers disposed within said recesses.

8. In a machine for uniting filaments comprising in combination, a rotatable hollow spindle

- having a portion for receiving a filament package, a cap rotatable with and removable from said spindle to overlie the top of a package thereon, separate annular guideways on said cap one above the other and travelers slidable there-around for receiving and guiding material at spaced intervals from a package on said spindle upwardly and inwardly onto a core passing through said spindle and cap, the said guideways being successively less in diameter upwardly of said cap.
9. In a machine for uniting filaments comprising in combination, a rotatable hollow spindle having a portion for receiving a filament package, a cap rotatable with and removable from said spindle to overlie the top of a package thereon, separate annular guideways on said cap one above the other and travelers slidable there-around for receiving and guiding material at spaced intervals from a package on said spindle upwardly and inwardly onto a core passing through said spindle and cap, the said guideways being successively less in diameter upwardly of said cap and the uppermost guideway having a sloping surface inclining towards said core.
10. In a machine for uniting filaments comprising in combination, a rotatable hollow spindle having a portion for receiving a filament package, a cap rotatable with and removable from said spindle to overlie the top of a package thereon, separate annular guideways on said cap one above the other and travelers slidable there-around for receiving and guiding material at spaced intervals from a package on said spindle upwardly and inwardly onto a core passing through said spindle and cap.
11. In a machine for uniting filaments comprising in combination, a rotatable hollow spindle having a portion for receiving a filament package, a cap rotatable with and removable from said spindle to overlie the top of a package thereon, separate annular guideways on said cap one above the other and travelers slidable there-around for receiving and guiding material at spaced intervals from a package on said spindle upwardly and inwardly onto a core passing through said spindle and cap, the uppermost guideway having a sloping surface inclining towards said core.
